(57) **CLAIM**

The ornamental design for a soap bar with integral cross, as shown and described.

DESCRIPTION

FIG. 1 is a front perspective view of a first embodiment of a soap bar with integral cross showing our new design thereof;

FIG. 2 is a reduced scale front elevational view of the first embodiment, the rear elevational view being a mirror image of the front elevational view;

FIG. 3 is a top view thereof, the bottom view being a mirror image of the top view; and

FIG. 4 is a right side elevational view thereof, the left side elevational view being a mirror image of the right side elevational view.

FIG. 5 is a front perspective view of a second embodiment of a soap bar with integral cross showing our new design thereof;

FIG. 6 is an enlarged scale front perspective view of the second embodiment with broken lines indicating the integral cross environment;

FIG. 7 is a reduced scale front elevational view of FIG. 5, the rear elevational view being a mirror image of the front elevational view;

FIG. 8 is a top view thereof, the bottom view being a mirror image of the top view; and,

FIG. 9 is a right side elevational view thereof, the left side elevational view being a mirror image of the right side elevational view.

The broken lines in FIG. 6 are for illustrative purposes only to indicate environment and form no part of the claimed design.
